Attorneys.

UNITED STATES PATENT OFFICE.

FRANCIS A. NOLAN, OF ST. PAUL, MINNESOTA.

RESILIENT TREAD FOR FOOTWEAR.

Application filed November 3, 1919. Serial No. 335,445. Renewed January 11, 1923.

To all whom it may concern:

Be it known that I, FRANCIS A. NOLAN, a citizen of the United States, residing at St. Paul, in the county of Ramsey and State 5 of Minnesota, have invented new and useful Improvements in Resilient Treads for Footwear, of which the following is a specification.

This invention relates to improvements in 10 resilient treads for shoes, boots and other footwear. More particularly the object of this invention is to provide improved means for securing treads most effectively to footwear. It has been common practice to pro- 15 vide rubber heels with metallic washers or metallic plates embedded therein and formed with nail holes, but as commonly constructed the nails must be made to register with the holes in the embedded washers or plate, 20 in order to insure that the nails pass directly and not slanting therethrough. It is also known that plates can be used that are not perforated, the surface of the plate being indented or roughened so that the nail can be 25 driven through the plate without being deflected, such construction being fully described in my Patent #1,219,991, granted on the 20th day of March, 1917, for rubber heels.

30 My present improvement provide a smooth plate so thin and so embedded in the resilient tread that the nails when driven through the tread and into the footwear will perforate the plate without the necessity of 35 guiding means or holes in the plate or washers being employed to prevent the point of the nail from glancing or bending when driven through the tread and into the footwear. A still further advantage attained by 40 my invention is that heels can be inter- changed from a right hand shoe to a left hand shoe to distribute the wear, the fastener plate permitting nails or other fastening means to be readily and effectively se- 45 cured through unperforated portions of the plate. With these and other objects in view my invention comprises the features of construction and combination of parts herein- after more particularly described and de- 50 fined in the claims.

In the accompanying drawing forming part of this specification, I have illustrat- 55 ed my invention as applied to a resilient heel structure, but it will be understood that the invention is equally applicable to soles and

other types of treads for use on shoes, boots, and other footwear.

In the drawing Fig. 1 is a plan of a rubber shoe heel looking at the bottom thereof, a portion being broken away and in section 60 to disclose the fastening plate which is embedded therein; Fig. 2 is a plan view of my improved fastening plate; Fig. 3 is a vertical section of a mold showing my improved heel and fastener therein, the section of said heel and fastener being taken on the line 3—3 of Fig. 1; Fig. 4 is a vertical section of a detail showing a portion of my improved fastener embedded in a portion of a heel and illustrating the action which transpires when 70 a fastener nail is driven through the heel for securing the heel on a shoe; Fig. 5 is a plan view of an alternative construction of fastener plate; Fig. 6 is a vertical section of a mold and heel illustrating the action which transpires in the mold when the fastener plate is not constructed in accordance with my improvements; Fig. 7 is a plan of the fastener plate shown in Fig. 6; Fig. 8 is a plan of a mold and fastener therein illustrating 80 an alternative construction of the mold engaging means and fastener; Fig. 9 is a plan of a mold and heel showing another alternative means for holding the fastener in the mold; Fig. 10 is a vertical longitudinal section of a heel illustrating an alternative construction of my improved fastener; Fig. 11 is a plan of my improved fastener which appears in Fig. 10, and Fig. 12 is a perspective partly in section of a detail 90 of the fastener illustrated in Fig. 11.

In the drawing A indicates a resilient heel tread made out of rubber, rubber composition or any other suitable resilient material. This heel may be made in any suitable shape 95 for use on foot-wear of any kind and is pro- vided with a nail fastening plate B or washer embedded therein or secured thereto. This fastener may be formed in any way desired either by moulding or cutting or the plate may be struck up with a die. The fastener as illustrated resembles in horizontal outline the heel but is of smaller surface area so that when embedded in the heel there is a marginal portion 10 of united material 105 constituting the tread body surrounding the fastener. The fastener is preferably formed with an opening or openings 11 of large or small area through which the resilient mate- 110 rial constituting the body of the tread above

and below the fastener is united by substantially solid portions of itself. Thus the fastener is intimately united with the body of the tread. The fastener is made out of 5 thin flexible metal of such thinness that it will readily yield to the point of a nail when the nail F (see Fig. 4) is driven upwardly against the fastener through the tread to fasten the tread on foot-wear. In readily 10 yielding to the point of a nail as stated, the fastener immediately and automatically forms an indenture 12 which prevents the point of the nail from deflecting or bending from its course when driven through the 15 tread. The thinness of the metal also permits the nail to be easily driven through the fastener and the fastener being constructed of metal is longitudinally unyielding to resist the lateral strain of the fastening nails 20 and is of sufficient strength to hold the heads of the nails and prevent the tread from being torn loose from foot-wear after it has been secured. The harder the metal 25 employed the thinner the plate should be. That portion of the fastener through which the nails are preferably secured is indicated by a surface zone C marked into or on the bottom surface of the tread. Thus in fastening the tread on foot-wear the nails are driven vertically through the tread at any portion indicated by the 30 surface zone C. In driving the nails through the thin metal fastener a jagged burr 13 forms around the nail which engages into the body of the tread and assists in holding the fastener in the tread. This burr also reinforces the strength of the fastener in preventing the tread from being torn away from the nails after the tread has 35 been secured on foot-wear.

In molding my improved fastener in the body of the tread a mold D may be provided with fastening pins 14 and 14' over which the fastener is placed, suitable perforations 40 15 and 16 being provided in the fastener to receive the positioning pins. In molding a tread a biscuit of rubber composition or other resilient material is placed in the mold. The fastener is then placed with its 45 rearward end over the pin 14 through the opening 15. The front openings 16 are preferably elongated longitudinally to guide the fastener down upon the pins 14' without distorting the shape of the fastener when the 50 uppermost biscuit of rubber composition is placed in the mold. The resilient material is then compressed and vulcanized in the usual manner. The back opening 15 closely surrounds the pin 14 to hold the rearward 55 end of the fastener longitudinally and laterally in position. In this manner the fastener is molded into the body of the heel in smooth flat condition, the holding means causing this operation to transpire. The

fastener being made out of flexible material 65 of such thinness as is employed requires this construction of mold or the equivalent thereof.

In Fig. 7 the fastener plate is shown provided with openings 18 which closely fit 70 over the mold positioning pins 19 (see Fig. 6) but in this construction, the fastener will not yield readily and lie flat in the mold when the rubber composition is compressed, the openings 18 not permitting free movement of the fastener. Consequently the fastener will become irregular in shape and not lie in a horizontal plane as by use of the construction of mold and plate illustrated in Figs. 3 and 5. In Fig. 8 the fastener has 80 a single opening 20 provided near the rearward end through which the positioner 21 engages. The forward pair of positioners 22 pass freely through a single large opening 23 in the fastener, being positioned so 85 as to permit free but limited longitudinal movement of the fastener by guiding the fastener longitudinally. This construction for positioning the fastener in the mold will also accomplish the result of molding the 90 tread with the fastener lying in a horizontal plane in the same manner as by use of the construction illustrated in Fig. 3. In Fig. 9 a triangular opening 24 is provided in the fastener through which the fastener positioning pins 25 in the mold pass freely, being spaced from the edges of said triangular opening. This construction will cause the fastener to assume a rough approximation 95 of the position desired in the body of the tread when the tread is molded with the fastener therein and allow the fastener to assume a position in a horizontal plane.

In Figs. 10, 11 and 12 I have illustrated an alternative construction of my invention in 105 which the body E of the tread is provided with the nail fastener 26 embedded in its upper surface and secured thereto by vulcanizing the fastener to the tread body and by burrs 27 formed by perforating the fastener and causing the surrounding edges of 110 the perforations to engage downwardly into the body of the tread when the tread is molded with the fastener therein as illustrated in Fig. 10. A flange 29 around the 115 edge of the fastener also augments the fastening means. The fastener 26 in the preferred construction illustrated and described 120 above is made out of thin metal material or its equivalent for the purpose of performing the improved function stated above. In fastening the tread E on footwear the nails 28 are driven upwardly through the body of 125 the tread and through the unperforated portion of the fastener.

While I have described and shown nails as the securing means passing through the tread and fastener, it will be understood that

screws or any other securing means may be employed as equivalent means for performing the functions thereof within the spirit of my invention. I have also shown a shoe heel in the drawing to which my improvement is applied but I wish it understood that my invention is equally applicable to treads used on heels, soles, half soles or any other form of tread for any and all kinds of foot wear or the equivalent thereof.

In accordance with the patent statutes I have described the principles of operation of my invention together with the apparatus which I now consider to represent the best embodiment thereof, but I desire to have it understood that the construction shown is only illustrative and that the invention can be carried out by other means and applied to uses other than those above set forth within the scope of the following claims.

Having described my invention, what I claim as new and desire to protect by Letters Patent, is:

25 1. A resilient tread having embedded therein a fastener to receive and hold a fastening nail, consisting of a thin flexible metal plate longitudinally unyielding to resist the lateral strain of the fastening nail 30 and adapted to resist and hold the head of the nail against passing through, said plate having a substantially smooth upper surface and being easily penetrable and readily yielding to the point of the nail to form an 35 indenture and prevent the point from de-

flecting when the nail is driven through the tread and fastener.

2. In combination with a resilient tread, a fastener, consisting of a thin flexible metal element secured to said tread, said element 40 having a substantially smooth upper surface and being easily penetrable and unyielding to resist the head of a nail against passing through and to resist lateral strain of the nail, and readily yielding to the point of a 45 nail to form an indenture and prevent the point from being deflected when the nail is driven through the tread and fastener.

3. As a new article of manufacture, a cushion tread provided with a metallic plate 50 embedded therein, said plate having a substantially smooth upper surface and being sufficiently thin and flexible to be easily indented by the fastening means employed to prevent deflection thereof and to be easily 55 penetrated by the fastening means when securing the tread on a support.

4. As a new article of manufacture, a cushion tread provided with a metallic plate 60 embedded therein having a substantially smooth upper surface and an opening through which the material of the tread connects and being sufficiently thin to be easily indented and penetrated by the fastening means.

Signed at St. Paul, in the county of Ramsey and State of Minnesota, this 29 day of October, 1919.

FRANCIS A. NOLAN.
